LIQUID TRAPPING DEVICE

Lyman A. Bliss, New York, N. Y., assignor to The
Linde Air Products Company, New York, N. Y.,
a corporation of Ohio

Application December 23, 1932, Serial No. 648,623

3 Claims. (Cl. 202—163)

This invention relates to liquid protective devices and particularly to liquid protective devices for pipes or conduits arranged for the passage of vapor from one portion of a chambered apparatus to another.

The invention has for its object generally an improved construction and arrangement of parts for devices of the character indicated which is efficient, economical, and readily manufactured.

More specifically, the invention has for its object the provision of an improved device for trapping liquid and preventing its passage through a conduit leading from the vapor space of a chamber containing both liquid and vapor to a second chamber where the presence of liquid is objectionable or injurious.

It is also an object to provide a desired margin of safety against the possibility of the passage of liquid in devices of the character indicated from the trap into the second chamber by constructing the device with means for increasing the resistance, particularly the hydrostatic head against which liquid must rise, to a predetermined value.

It is a further object to provide devices of the character indicated with traps which may be drained, the traps being constructed to be self-draining in some instances.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawing, in which:

Fig. 1 is a fragmentary view mainly in section showing a chambered apparatus provided with a liquid protective device constructed in accordance with the invention; and

Fig. 2 is a fragmentary view, similar to Fig. 1, but showing a modified form of the invention.

Referring now to the drawing, and particularly to Fig. 1, 10 denotes generally an apparatus which may be a rectifying column for liquefied gases, for example, liquid oxygen, which has a chamber 11 in the lower portion of which there is a heat exchanging means 12 for vaporizing the liquid therein. From an exit of the vapor space of this chamber there leads a conduit or passage 13 to an inlet of a second chamber in the apparatus, which in the column shown comprises an auxiliary heat exchanging means or condensing chamber 14, this passage having a relatively extended vertical portion 13' and a depending connection

15 that leads to the lower header of this second chamber, this second chamber also being provided with a withdrawal connection 16. Rectification columns for liquefied gases are with advantage provided with condensing chambers, such as here shown at 14, where it is desired to effect a high degree of purification, and as set forth in the co-pending application of Walter F. Moeller now Patent No. 1,967,717, dated July 24, 1934.

In accordance with the practice of the present invention, the passage 13 is provided with a trap device 18 at the base of the vertical portion, arranged for catching any liquid which may enter the passage from the chamber 11, since it is desirable to prevent the passage of such liquid into the chamber 14. This trap device may have any convenient form, for example a U shaped trap which has one leg communicating directly with the vapor space of the first chamber, and its other leg in communication with the vertical section 13'. The trap is also preferably provided with a liquid withdrawal means comprising a connection, as indicated at 19, and has means, for example a gage glass 20, for indicating the presence of liquid in the trap device. Whenever liquid is sighted in the trap by the operator, the withdrawal connections 19 are opened to withdraw all liquid contained therein, after which it is closed so that vapor can again pass freely from the first chamber to the second.

In order that the chamber 14 may have the desired protection against the passage thereinto of any liquid from the vapor space of the first chamber or from the trap device 18, the vertical portion 13' is extended upwardly a predetermined distance in excess of that normally separating the first and second chambers, and a second trap 21 inserted in the vapor passage at the head of the vertical portion; the value of the hydrostatic head against which liquid must rise from the first trap device is then determined by the distance the two trap devices are separated. The value given is, of course, such as to impart the desired margin of safety. The vertical portion 13' thus provided rises upwardly to a point 45 which in general is materially above the place where the connection 15 enters the second chamber. The second trap device 21 may have any convenient form, for example, that of an inverted U, as shown in the drawing. The inverted U 21 is also preferably tapped, for example, by the provision of a passage 22, in order that vapor may be led away when desired.

In operation, it is seen from the description above that the normal liquid level in the chamber 11 is below the entrance to the passage 13. In normal operation, vapor passes freely from the chamber 11 to the chamber 14. If for any reason liquid enters the passage 13, it is seen to accumulate in the trap device 18 until its presence

is made evident in the gage glass 20 when the operator will withdraw the same through the conduit 19. During this period of liquid accumulation prior to the withdrawal through the conduit 19, the vapor will generally bubble through the liquid. The increasing of the hydrostatic head through which liquid must rise by the provision of the inverted U 21, is seen to function not only to stop the passage of liquid, but also to make more likely the passage of the vapor through the liquid in the trap device 18 in bubble form.

In Fig. 2, a modified arrangement of the device for protecting the chamber 14 against the entry of liquid is shown. Where the conduit 23 is indicated as leading from the vapor space of the chamber 11 and includes not only a U portion 24 of a primary trap, but also an auxiliary trap comprising a small chamber 25 through the bottom 20 of which the passage 23 enters and extends upwardly as a small pipe portion 23' terminating short of the upper closure of the auxiliary chamber 25. From the top of the auxiliary chamber 25, the passage is continued through an inverted U portion 26 to a connection 27 that communicates with the chamber 14.

The auxiliary chamber 25 is designed to receive and separate from the vapor any liquid that may come over in the passage 23. Such liquid as initially is caught in the trap 24 is ultimately discharged into the auxiliary chamber 25. This auxiliary chamber is made self-draining by the provision of a conduit 28 which leads from the bottom of the auxiliary chamber and communicates with the chamber 11 below the liquid level therein, this connection being preferably provided with a control means 29, such as a hand valve. In order that the operation of this form of device may be watched, a gage glass 30 is preferably provided to show the level of any liquid that may have accumulated in the auxiliary chamber 25.

In operation, this second form of device is seen to be similar to that shown in Fig. 1, except that the auxiliary chamber 25 is made self-draining by means of the connection 28, the hand valve 29 being adjusted to accommodate the flow from the auxiliary chamber 25 to the main chamber 11 at any desired rate.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:

1. In a device of the character described, the combination with an apparatus including a liquid heating and vaporizing chamber having a vapor space and a second chamber located in heat exchanging relation with respect to the first chamber and adapted to receive vapor therefrom, of a passage member extending from an exit of the vapor space of said first named chamber to an inlet of said second named chamber, said passage member including a relatively vertically extending portion, a trap device at the base of said vertical portion disposed below said vapor exit and provided with a through passage for vapor and with liquid separating and withdrawing means, and a second trap device at the top of said

vertical portion and disposed above said inlet of said second chamber and provided with a through passage for vapor; said vertical portion of said passage member being of a length proportioned to provide a predetermined hydrostatic head and resistance against the rising of liquid therein when liquid tends to pass from the first named trap device into the second, said passage member and trap devices being arranged to provide a relatively free path for vapor passing from the vapor space of the first named chamber to said second named chamber.

2. In a device of the character described, the combination with an apparatus including a liquid heating and vaporizing chamber having a vapor space and a second chamber located in heat exchanging relation with respect to the first chamber and adapted to receive vapor therefrom, of a passage member extending from an exit of the vapor space of said first named chamber to an inlet of said second named chamber, said passage member including a relatively vertically extending portion, a trap device at the base of said vertical portion disposed below said vapor exit and provided with a through passage for vapor and with liquid separating and withdrawing means, a second trap device at the top of said vertical portion and disposed above said inlet of said second chamber and provided with a through passage for vapor, and a connection for returning the liquid withdrawn from the first named trap to the liquid space of said first named chamber; said vertical portion of said passage member being of a length proportioned to provide a predetermined hydrostatic head and resistance against the rising of liquid therein when liquid tends to pass from the first named trap device into the second, said passage member and trap devices being arranged to provide a relatively free path for vapor passing from the vapor space of the first named chamber to said second named chamber.

3. In a device of the character described, the combination with an apparatus including a liquid heating and vaporizing chamber having a vapor space and a second chamber located in the first chamber so as to be cooled and adapted to receive vapor therefrom, of a passage member extending from an exit of the vapor space of said first named chamber to an inlet of said second named chamber, said passage member including a relatively vertically extending portion, a trap device at the base of said vertical portion disposed below said vapor exit and provided with a through passage for vapor and with liquid separating and withdrawing means, a second trap device at the top of said vertical portion and disposed above said inlet of said second chamber and provided with a through passage for vapor, a connection for returning the liquid withdrawn from the first named trap to the liquid space of said first named chamber, and means for visually indicating the presence of liquid in the first named trap to an attendant; said vertical portion of said passage member being of a length proportioned to provide a predetermined hydrostatic head and resistance against the rising of liquid therein when liquid tends to pass from the first named trap device into the second, said passage member and trap devices being arranged to provide a relatively free path for vapor passing from the vapor space of the first named chamber to said second named chamber.
